UNITED STATES PATENT OFFICE

LEROY EDMUND STACKPOLE, OF SANFORD, MAINE

COLLAPSIBLE BOOK HOLDER

Application filed December 28, 1927. Serial No. 243,077.

The present invention relates to improvements in book holders and has for its principal object to provide a book holder that is especially adapted for attachment to a bed in order that the occupant of the bed may read the book, newspaper or other periodical supported on the book holder.

One of the important objects of the present invention is to provide a book holder wherein means is associated with the holder whereby to permit the same to be adjusted in various directions.

A still further object is to provide a collapsible book holder that can be readily and easily attached or detached with respect to one of the bed posts, the book holder being readily collapsed and disposed adjacent the bed post when not in use, and being readily extended for use, means being provided for bracing the extensible means.

A still further object is to provide a collapsible book holder of the above mentioned character which is simple in construction, inexpensive, strong and durable and further well adapted to the purpose for which it is designed.

Other objects and advantages of the invention will become apparent from the following description when taken in connection with the accompanying drawing.

In the accompanying drawing wherein like reference characters indicate corresponding parts throughout the several views:

Figure 1 is a perspective view of the book holder embodying my invention showing the same in its extended position and attached to a bed post, and

Figure 2 is an elevational view of the same frame of the book holder showing the supplemental frame attached thereto.

In the drawing wherein for the purpose of illustration is shown the preferred embodiment of my invention, the numeral 1 designates a vertically disposed plate-like bracket, the same being provided with the bed post engaging members 2 and 3, respectively. These bed post engaging members are preferably covered with rubber tubing or the like to prevent marring of the bed post and the manner in which these elements engage

around the bed post is clearly shown in Figure 1.

A similar plate like bracket 4 is formed with a longitudinally extending slot 5 and this bracket 4 is operatively connected with the bracket 1 through the medium of the lazy tong structure designated generally by the numeral 6. The lazy tong structure includes a series of vertically disposed intersecting cross arms that are pivotally secured together at their points of intersection and are further pivotally connected together at their adjacent ends in the manner well known in the art.

The lower end of the innermost cross arm 7 is pivotally secured to the lower end of the bracket 1, while the upper end of the innermost arm 8 is operatively connected to the upper end of the bracket 1 through the medium of the connecting link 9.

In a similar manner the upper end of the outermost arm 10 is pivotally connected to the upper end of the bracket 4 while the lower end of the outermost arm 11 is operatively connected to the lower end of the bracket 4 through the medium of the link 12.

In Figure 1 of the drawing, the lazy tong structure is disclosed as being extended and for the purpose of maintaining the lazy tong structure in its proper vertical position there is provided the horizontally disposed bracing means designated generally by the numeral 13, said bracing means also consisting of a lazy tong structure. The lazy tong structure constituting the bracing means is however slightly different in its construction than the vertically disposed lazy tong structure forming the connection between the brackets 1 and 4, and as is clearly illustrated in the drawing, said horizontally disposed lazy tong structure comprises a plurality of angular brackets or lugs 14 that are secured on the opposite sides of the points of intersection of the cross arms of the vertically disposed lazy tong structure. Pairs of pivotally connected arms 15 and 16 are pivotally secured at their outer ends to the respective brackets on the respective sides of the vertically disposed lazy tong structure 6 and manifestly when the lazy tong structure 6 is in its

extended position, the horizontally disposed lazy tong structure will also be extended.

Also when the lazy tong structure 6 is collapsed, the lazy tong structure 13 constitutes the bracing means for the aforementioned lazy tong structure 6 will also be collapsed whereby to provide a compact structure that will not occupy any considerable amount of space.

10 The book supporting frame is designated generally by the numeral 17 and the same comprises the central frame bar 18. The upper relatively narrow bars or strips 19 and 20 are pivotally secured at their inner ends to the outer or front face of the upper end of the central vertical bar 18. Similar bars 21 and 22 are secured in a pivoted manner at their inner ends to the lower end of the central bar 18. The outer ends of the upper and lower horizontal bars are operatively connected to the upper and lower ends of the respective side bars 23 and 24. Intermediate brace bars 25 and 26 are secured at their ends to the side bars 23 and 24 respectively at the central portion thereof, the inner ends of these brace bars being operatively connected to the intermediate portion of the vertical central bar 18. A strip 27 is secured on the front face of the central bar 18 to provide a rest or shoulder for the inner ends of the central brace bars 25 and 26 as clearly illustrated in Figure 1. This will maintain the frame in its assembled position and pivoted at each of the corners of the frame is the spring clip 28 that will engage the four corners of a book and maintain the same in proper position on the frame. In addition, wire fingers 29 are secured to the side bars for holding the pages of the book in an open position, it being understood of course that the spring clips 28 will engage the cover of the book for holding the same open.

15 The frame 17 is suspended from the bracket 4 and the suspension means comprises an upper arm 30 that is formed at its upper end with an enlarged eye through which extends a bolt 31 that is operable within the slot 5 formed in the plate-like bracket 4, a wing nut (not shown) being threaded on the threaded 20 end of the bolt for holding the arm 30 in any vertically adjusted position on the bracket. The lower end of this arm is disposed laterally for cooperation with the upwardly disposed end of the lower arm 32, the lower end 25 of which is pivotally secured to the rear face of the upper portion of the central bar 18 of the book frame 17 through the medium of the bolt 33. The laterally disposed abutting ends of the upper and lower arms are formed with 30 registering openings to receive the bolt 34 and a nut 35 is threaded on the end of the bolt. This construction provides a means whereby the book frame may be adjusted in various directions and in various positions with respect to the bracket 4 so that the frame may

be properly positioned when the book holder is extended in order to enable the occupant of the bed to properly read from the book that is supported on the frame.

20 In order to increase the size of the frame so that books or newspapers of larger size can be supported on the holder, I have provided a supplemental frame designated generally by the numeral 36 and this frame includes a pair of upper bar members 37 and 38 that are pivotally connected together at their adjacent ends, a similar pair of lower bar members being designated by the numerals 39 and 40, respectively. The outer ends of the upper and lower bars are secured to the respective ends of the side bars 41 and 42. This provides a substantially rectangular shaped frame, and the upper bars 37 and 38 are formed with suitable notches in the upper edges thereof to engage headed pins that are carried by the rear side of the upper bars 19 and 20 respectively of the main frame 17, the upper bars of the supplemental frame will be disposed in alignment with the upper bars of the main frame and the end bars of the supplemental frame will be disposed beyond the end or side bars of the main frame, and also the bottom bars of the supplemental frame will be disposed below the bottom bars of the main frame. This is clearly illustrated in Figure 2 of the drawing.

25 Brace bars 43 and 44 are pivotally secured at their outer ends to the intermediate portion of the side bars 41 and 42, respectively, of the supplemental frame 36 and the inner ends of these brace bars are formed with hooks for detachable engagement over headed pins 45 and 46 arranged on the side bars 23 and 24 respectively of the main frame 17, and the manner in which these brace bars cooperate with the headed pins is clearly 30 shown in Figure 2. This construction is further strengthened by having the free ends of the lower spring clips 28 formed with hooks 47 that engage over suitable headed pins 48 that are carried by the lower horizontal bars 39 and 40 of the supplemental frame 36 when the lower spring clips are disposed downwardly in a vertical position as also clearly shown in Figure 2.

35 The supplemental frame is provided with a series of spring clips designated by the numeral 49 similar to the spring clip 28 associated with the main frame 17 and in a similar manner the side bars of the supplemental frame carry the spring wire fingers 50 that are similar to the spring wire fingers 29 secured on the side bars of the main frame. In this manner, a relatively large book or newspaper can be properly supported on the frames when the same are assembled together. It is of course to be understood that books of a smaller size will be supported on the main frame and the supplemental frame

can be readily and easily removed or attached whenever necessary.

It will thus be seen from the foregoing description that I have provided a novel book holder that can be readily and easily adjusted to a bed post, and when not in use, the book holder may be collapsed or folded in such a manner as to provide a compact structure for disposition adjacent the bed post.

10 While I have shown the preferred embodiment of my invention, it is to be understood that various changes in the size, shape and arrangement of parts may be resorted to without departing from the spirit and scope 15 of the appended claim.

Having thus described the invention, what I claim as new is:—

20 In structure of the class described, a bracket for attachment to a support, an additional bracket, a vertically arranged lazy tong structure including a series of vertically disposed intersecting cross arms pivotally secured together at their points of intersection, the outermost arms being pivotally connected to the adjacent brackets, a horizontally arranged lazy tong structure for bracing the vertically arranged lazy tong structure, said horizontally disposed lazy 25 tong structure including a plurality of angular lugs secured on the opposite sides of the points of intersection of the cross arms of the vertically disposed lazy tong structure, pivotally connected arms secured at their outer 30 ends to their respective lugs on the respective sides of the vertically disposed lazy tong structure, both of said lazy tong structures being adapted for simultaneous operation.

35 In testimony whereof I affix my signature.
40 LEROY EDMUND STACKPOLE.
